UNITED STATES PATENT OFFICE.

MARTIN L. DIGBY, OF RISING STAR, TEXAS.

PLOW-CLEVIS.

No. 877,413.

Specification of Letters Patent.

Patented Jan. 21, 1908.

Application filed August 19, 1907. Serial No. 389,211.

To all whom it may concern:

Be it known that I, MARTIN L. DIGBY, a citizen of the United States, residing at Rising Star, in the county of Eastland and State 5 of Texas, have invented certain new and useful Improvements in a Plow-Clevis; and I do declare the following to be a full, clear, and exact description of the invention, such as will enable others skilled in the art to which 10 it appertains to make and use the same.

This invention relates to improvements in plow clevises.

The object of the invention is to provide a clevis for plows which is adapted to be adjusted laterally and vertically to regulate the 15 cut of the plow share.

A further object is to provide a plow clevis of this character which will be simple, strong and durable in construction, efficient in operation and well adapted to the purpose for 20 which it is designed.

With these objects in view, the invention consists of certain novel features of construction, combination and arrangement of parts 25 as will be more fully described and particularly pointed out in the appended claims.

In the accompanying drawings, Figure 1 is a plan view of a clevis constructed in accordance with the invention; Fig. 2 is a side 30 view; Fig. 3 is a central vertical longitudinal sectional view, and Fig. 4 is a detailed horizontal sectional view of the same.

Referring more particularly to the drawings, 1 denotes the clevis, which consists of a 35 body portion in the form of a horizontally disposed, substantially rectangular frame, 2, comprising a front bar, 3, rear bar, 4, intermediate bar, 5, and end bars, 6, which connect the ends of said front, rear and intermediate bars, 40 as shown. To the rear bar, 4, is connected a pair of integrally formed attaching plates, 7, which are spaced apart and project rearwardly from the bar 4. The plates 7 are adapted to be engaged with the opposite sides 45 of the plow beam, and to be bolted or otherwise connected thereto. In the front bar 3 is formed a series of vertically disposed apertures, 8, the purpose of which will hereinafter appear.

Slidably mounted on the apertured bar 3 of 50 the frame is a sleeve 9, having on its opposite ends radially projecting annular flanges, 10. On the sleeve 9 is secured a circular adjusting plate, 12, on the inner edge of which is formed 55 a rearwardly projecting guide lug, 13, having formed therein a transversely disposed pas-

sage or opening, 14, which is slidably engaged with the intermediate bar, 5, of the frame, 2. The inner end of the lug 13 bears on and slides against the inner side of the rear bar 4 of the frame. By thus connecting the plate 12 with the sleeve 9 and with the intermediate bar 5, said plate may be adjusted laterally in either direction on the frame, 2. The sleeve 9 and plate 12 are held in their adjusted position by means of a locking pin, 15, which is adapted to be inserted through a hole, 16, formed in the upper side or edge of the plate, 12, and into one of a series of holes or openings formed in the front bar 3 of the 60 frame.

On the sleeve 9 between the plate 12 and the flanges 10 is loosely mounted a pair of draft rings, 17, which are formed on one edge with radially projecting oppositely disposed 65 extensions 18, connected together at their outer ends by a spacing block, 19, in which is swiveled the inner end of a draft hook, 20. In the rings 17 adjacent to the inner end of the extension 18 are formed alined openings 70 21, which are adapted to be brought into alinement with one of an annular series of openings, or holes, 22, formed in the circular adjusting plate, 12, and through said alined holes in the rings 17 and plate 12 is adapted 75 to be inserted a locking pin, 23, which holds or locks the draft rings and hook 20 in any desired position, thus providing means whereby the plow point may be directed into the ground to a greater or less degree, for the 80 forming of furrows of different depths.

By providing for the lateral adjustment of the plate 12 and the draft rings as hereinbefore described, more or less land may be given to the plow share, thus providing for 85 forming furrows of different width.

A clevis constructed as herein shown and described may be quickly and easily adjusted to vary the position of the plow point and share to cause the same to form furrows of 90 different width and depth.

Having thus fully described my invention, what I claim as new and desire to secure by Letters-Patent, is:

1. A clevis comprising a frame, a sleeve 105 slidably mounted on said frame, draft rings on said sleeve and means to adjustably connect the latter on said frame, whereby the action of the plow may be varied, substantially as described.

2. A clevis comprising a substantially rectangular frame, means to attach the same

to the end of a plow beam, a sleeve slidably mounted on said frame, an adjusting bar connected to said sleeve and adapted to slidably engage one of the bars of said frame, 5 means to lock said plate and sleeve in their adjusted positions, clamping rings loosely mounted to turn on said sleeve, means to lock said rings in their adjusted position, and a draft hook connected to said rings, substantially as described.

3. A clevis comprising a rectangular frame consisting of an apertured front bar, a rear bar, an intermediate bar and end bars adapted to connect said front, rear and intermediate bars, rearwardly projecting attaching plates formed on said rear bar and adapted to be secured to a plow beam, a sleeve slidably mounted on said front apertured bar of the frame, an adjusting plate mounted on 10 said sleeve, an apertured lug projecting from said plate and adapted to slidably engage the intermediate bar of said frame, means to lock said sleeve and plate in their adjusted position on the bars of said frame, draft rings 15 loosely mounted to turn on said sleeve, means to lock said rings in adjusted position on said sleeve, and a draft hook connected to said rings, substantially as described.

4. A plow clevis comprising a rectangular frame consisting of an apertured front bar, 20 a rear bar, an intermediate bar and end bars connecting said front, rear and intermediate

bars, means to attach said frame with the plow beam, an apertured sleeve slidably mounted on said sleeve, said plate having 35 formed therein an annular series of transversely disposed holes, a rearwardly projecting apertured lug on said plate adapted to engage the intermediate bar of said frame, radially projecting annular flanges formed 40 on the outer ends of said sleeve, draft rings loosely mounted on the sleeve to turn between said flanges and said adjusting plate, said rings having formed therein aligned apertures adapted to be brought into alignment 45 with the apertures in said plate, a locking pin adapted to be inserted through a vertical aperture formed in said adjusting plate and through one of the series of apertures formed in the front bar of the frame, whereby said 50 adjusting plate and draft rings are held in their lateral adjusted positions, and a locking pin adapted to be inserted through the aligned openings in said draft rings and adjusting plate to lock said rings in their adjusted positions, substantially as described.

In testimony whereof I have hereunto set my hand in presence of two subscribing witnesses.

MARTIN L. DIGBY.
